LAMP SHADES AND METHODS OF MAKING THE SAME

Samuel Weisbrod, Philadelphia, Pa.

Application April 16, 1953, Serial No. 349,267

10 Claims. (C.i. 240—108)

This invention relates to lamp shades and methods of making the same and more particularly to the type in which the fabric covering is secured entirely by machine applied stitches.

It is the principal object of the present invention to provide a lamp shade having a covering which is entirely secured by the use of machine stitching.

It is a further object of the present invention to provide a lamp shade which can be quickly and easily constructed by relatively unskilled labor.

It is a further object of the present invention to provide a lamp shade in which either the inside or outside coverings may be applied first, as desired.

It is a further object of the present invention to provide a lamp shade in which the inside and outside coverings may be secured either concurrently or successively and held in place by machine applied stitching.

It is a further object of the present invention to provide improved methods of mounting and securing the inside and outside coverings of a lamp shade.

Other objects and advantageous features of the invention will be apparent from the specification and claims.

The nature and characteristic features of the present invention will be more readily understood from the following description, taken in connection with the accompanying drawings forming part hereof, in which:

Figure 1 is a front elevational view of a preferred embodiment of the present invention showing one layer of covering in position;

Fig. 2 is a fragmentary vertical sectional view taken approximately on the line 2—2 of Fig. 1;

Fig. 3 is a fragmentary vertical sectional view taken approximately on the line 3—3 of Fig. 1;

Fig. 4 is a front elevational view showing two layers of covering in position;

Fig. 5 is a fragmentary vertical sectional view taken approximately on the line 5—5 of Fig. 4;

Fig. 6 is a fragmentary vertical sectional view taken approximately on the line 6—6 of Fig. 4;

Fig. 7 is a front elevational view showing the trimming strips in position and the lamp shade fully assembled;

Fig. 8 is a fragmentary vertical sectional view taken approximately on the line 8—8 of Fig. 7;

Fig. 9 is a fragmentary vertical sectional view taken approximately on the line 9—9 of Fig. 7.

Fig. 10 is a fragmentary vertical sectional view, similar to Fig. 2, showing the inner layer applied first;

Fig. 11 is a fragmentary vertical sectional view, similar to Fig. 3, showing the inner layer applied first;

Fig. 12 is a fragmentary vertical sectional view, similar to Fig. 5, showing the inner layer applied first;

Fig. 13 is a fragmentary vertical sectional view, similar to Fig. 6, showing the inner layer applied first;

Fig. 14 is a fragmentary vertical sectional view, similar to Fig. 8, showing the inner layer applied first;

Fig. 15 is a fragmentary vertical sectional view, similar to Fig. 9, showing the inner layer applied first;

2

Fig. 16 is a fragmentary vertical sectional view, similar to Fig. 5, showing the presewed layers applied concurrently; and

Fig. 17 is a fragmentary vertical sectional view, similar to Fig. 8, showing the presewed layers applied concurrently.

It should, of course, be understood that the description and drawings herein are illustrative merely, and that various modifications and changes may be made in the structure disclosed without departing from the spirit of the invention.

Like numerals refer to like parts throughout the several views.

Referring now more particularly to the drawings, in accordance with the present invention the lamp shade has a frame preferably of wire, and of any suitable configuration for the shape desired. The frame preferably includes a top vertically flat horizontal metal ring 20 and a lower vertically flat horizontal metal ring 21 held in parallel spaced relation by a plurality of upright metal ribs 22. The ribs 22 may be of a straight or curved configuration and disposed in either an inclined or vertical manner as determined by the shape of the finished shade desired. A spider (not shown) is provided in the conventional manner in fixed engagement with the top ring 20 for facilitating and effecting the support of the lamp shade.

A flat tape 23, of suitable textile material or heavy paper, is provided spirally wound perimetrical about the ring 20 and held in engagement therewith in any suitable manner. The tape 23 may be wound so that there may be provided either one or more layers of the tape 23 on the ring 20 as desired, one layer being preferable. A similar tape 24 is provided for the ring 21.

The lampshade of the present invention has, enclosing the metal frame, an outside layer or covering 25, preferably of suitable textile material, such as silk or the like, and an inside layer or liner 26 of suitable material. The vertical terminal edges of the layer 25 are sewed together vertically to impart the layer 25 a substantially hollow tubular configuration. The layer 26 is similarly formed.

The order of application of the layers 25 and 26 to the frame is not material and either layer 25 or 26 may be applied first. For the purposes of description the outside layer 25 will be considered as applied first. It is likewise not material whether the layers 25 and 26 are first secured at the top or bottom of the frame, initial top securing providing somewhat greater facility in obtaining the desired tautness of the covering material. The approach from the top of the frame will be considered for the purposes of explanation.

Referring more particularly to Fig. 2, the layer 25 is positioned with its upper portion on the frame extending for a short distance above the upper or outer edge face of the ring 20 so that a horizontal row of sewing machine stitches 27 may be applied passing through one portion of the layer 25 at the topmost portion thereof as well as the tape 23. The row of stitches 27 is applied just above the top edge face of the ring 20 so that that face of the ring 20 may act as a guide for the needle of the sewing machine used to apply the row of stitches 27. The layer 25 is pulled downwardly to obtain the desired degree of smoothness and tautness and the lower portion thereof fastened to the bottom of the frame by a row of machine applied stitches 28, as shown in Fig. 3, in a manner similar to that employed for securing the upper portion of the layer 25. At the lower portion of the layer 25, the row of stitches 28 is applied just below the bottommost edge face of the ring 21 and that face is used as a guide for the needle in a manner similar to that previously described. The row of stitches 28 secures the lower portion of the layer 25 to the ring 21 by passing through the tape 24 which is

in fixed encompassing engagement with the ring 21 in a manner similar to the tape 25 on the ring 20.

Referring now to Fig. 5, the inside layer 26 is applied to the frame by positioning the upper portion thereof over the interior of the ring 20 in overlapping arrangement so that the upper portion of the layer 25 is covered by the upper portion of the layer 26 to a point below the row of stitches 27. A horizontal row of machine stitches 29 is applied at the same location as the stitches 27 thus securing the upper portion of the layer 26 to the layer 25 and the tape 23. As in previous sewing operations, the topmost edge face of the ring 20 is used as a needle guide. The stitches 29 pass through two thicknesses of the upper portion of the layer 26, one thickness on the inner side of the ring 20 and the second thickness on the outer side of the ring 20. The layer 26 is then pulled downwardly to obtain the desired degree of smoothness and tautness and at the lower portion thereof, as shown in Fig. 6 is brought into overlapping relation with the outer edge face of the ring 21 and the contiguous stitched portion of the cover layer 25. A horizontal row of stitches 30 is applied, at the same location as the stitches 28, passing through the lower portion of the layer 25, the tape 24 and two thicknesses of the lower portion of the layer 26 to secure the layer 26 in place. The bottommost edge face of the ring 21 serves as a needle guide during the machine sewing operation.

A trimming strip or band 31 is provided at the upper portion of the frame and is secured to the ring 20 on the inner side thereof by a horizontal row of machine stitches 32 which passes through one thickness of the strip 31. The row of stitches 32 is applied at the same location as the rows of stitches 27 and 29, and using the topmost edge face of the ring 20 as a guide for the sewing needle. The stitches 32 pass through the layers 25 and 26 and the tape 23, as shown in Fig. 8, to secure the strip 31 in position. The strip 31 is secured on the inner part only of the ring 20 by the stitches 32 and is then folded over the top and outer edge of the ring 20, being held in place by the tension applied thereto by the folding. In similar manner, a trimming strip or band 33 is provided secured in position by a horizontal row of stitches 34, which engages the tape 24 on the ring 21. The strip 33 is secured by the stitches 34 and is then folded under the bottom and outer edge face of the ring 21, being held in place by tension applied thereto by the folding. Like the stitches 32, the stitches 34 pass through the layers 25 and 26 and the tape 24 as shown in Fig. 9 to secure the strip 33 in position.

It has been previously stated that the order of application of the layers 25 and 26 may be selected as desired. In Figs. 1 to 9, inclusive, the application of the outer layer 25 first is shown; in Figs. 10 to 15, inclusive, the application of the new inner layer 26 first is shown. Referring to Fig. 10, the upper portion of the layer 26 is positioned on the frame and secured to the upper edge face of the ring 20 by a horizontal row of sewing machine stitches 50 passing through the layer 26 and the tape 23. As previously described the topmost face of the ring 20 is used as a needle guide. The lower portion of the layer 26 is pulled downwardly to obtain a smooth and taut surface thereon and is then secured, in a similar manner, as shown in Fig. 11, to the tape 24 of the ring 21 by a horizontal row of stitches 51 using the bottommost face of the ring 21 as a needle guide. The outer layer 25 is secured to the tapes 23 and 24 on the rings 20 and 21 in a manner similar to that used in applying the layer 26 previously, by horizontal rows of stitches 52 and 53 respectively, as shown in Figs. 12 and 13. Similarly, the trimming strips 31 and 33 are secured as before by rows of stitches 54 and 55, as shown in Figs. 14 and 15.

If desired, in the manufacture of lamp shades of the

character herein disclosed, the layers 25 and 26 may be secured along marginal edges thereof, in any suitable manner such as by a line of stitching 60, before applying to the frame. After the layers 25 and 26 have been fastened together they are positioned on either side of and superposed on the ring 20 as shown in Fig. 16. The lower portions of the layers 25 and 26 may be secured as before with the order of application immaterial, except that the first applied-layer is preferably somewhat shorter than the later-applied layer and therefore the order of application of the layers 25 and 26 should be determined beforehand so that the desired length of material is available. Otherwise, both of the layers 25 and 26 would have to be provided at the longer dimension and the first-applied layer preferably trimmed off to meet the desired dimensional requirement. It is not absolutely necessary to trim off the excess of the first-applied layer, but such would be preferable in order to avoid a lumpy condition at that location. The trimming strip 31 as shown in Fig. 17, is then applied as previously described. Similarly, the trimming strip 33 is applied as before.

I claim:

1. A lamp shade comprising an uppermost ring, a lowermost ring, a plurality of ribs for maintaining said rings in spaced axial relation, an enclosing member encasing said uppermost ring and having a portion extending axially upwardly beyond said uppermost ring and disposed above said ribs, a second enclosing member enclosing said lowermost ring and having a portion extending axially downwardly beyond said lowermost ring and disposed below said ribs, a cover layer secured at its upper part to said first mentioned portion by a continuous horizontal row of stitches disposed upwardly beyond said uppermost ring and secured at its lower part to said second mentioned portion by a continuous horizontal row of stitches disposed downwardly beyond said lowermost ring, said cover layer between said rows of stitches being under tension by said rows of stitches.

2. A lamp shade comprising an uppermost ring, a lowermost ring, a plurality of ribs for maintaining said rings in spaced axial relation, an enclosing member encasing said uppermost ring and having a portion extending axially upwardly beyond said upper ring and disposed above said ribs, a second enclosing member enclosing said lower ring and having a portion extending axially beyond said lower ring and disposed below said ribs, a first cover layer having a marginal part engaging one said portion of one of said members and having the other marginal part secured to said portion of the other of said members axially outwardly beyond its ring by a continuous row of stitches, and a second cover layer having a marginal part engaging one said portion of one of said members and having the other marginal part secured to one said portion of another of said members by a continuous row of stitches, both said cover layers being held under tension by their respective rows of stitches.

3. A lamp shade comprising an uppermost ring, a lowermost ring, a plurality of ribs for maintaining said rings in spaced axial relation, an enclosing member encasing said uppermost ring and having a portion extending axially upwardly beyond said upper ring and disposed above said ribs, a second enclosing member enclosing said lower ring and having a portion extending axially beyond said lower ring and disposed below said ribs, a first cover layer having its upper marginal part secured to said first mentioned portion by a continuous horizontal row of machine stitches disposed upwardly beyond said uppermost ring and having its lower marginal part secured to said second mentioned portion by a continuous horizontal row of machine stitches disposed downwardly beyond said lowermost ring, and a second cover layer having its upper marginal part secured by a continuous horizontal row of machine stitches superposed at the same location on said first enclosing member as said first mentioned row of

stitches and having its lower marginal part secured by a continuous horizontal row of machine stitches superposed at the same location on said second enclosing member as said second mentioned row of stitches.

4. A lamp shade as defined in claim 3 in which a trimming strip is interiorly secured to one of said portions and extends outwardly and axially in overlapped relation to the contiguous marginal parts of said cover layers.

5. A lamp shade comprising an uppermost ring, a lowermost ring, a plurality of ribs for maintaining said rings in spaced axial relation, an enclosing member encasing said uppermost ring and having a portion extending axially upwardly beyond said upper ring and disposed above said ribs, a second enclosing member encasing said lower ring and having a portion extending axially beyond said lower ring and disposed below said ribs, a first cover layer having its upper marginal part secured to said first mentioned portion by a continuous horizontal row of machine stitches disposed upwardly beyond said uppermost ring and having its lower marginal part secured to said second mentioned portion by a continuous horizontal row of machine stitches disposed downwardly beyond said lowermost ring, and a second cover layer having its upper marginal part secured by a continuous horizontal row of machine stitches superposed at the same location on said first enclosing member as said first mentioned row of stitches and having its lower marginal part secured by a continuous horizontal row of machine stitches superposed at the same location on said second enclosing member as said second mentioned row of stitches, said cover layers being held in tension by their respective rows of stitches, and one of the cover layers having marginal parts in overlapped relation to marginal parts of the other cover layer.

6. The method of manufacturing fabric lamp shades having lowermost and uppermost rings held in spaced axial relation comprising applying an enclosing covering to at least one of said rings, securing a fabric covering

layer to one of said enclosing coverings axially outwardly beyond its ring by a continuous row of machine stitches, and securing another covering layer to the same enclosing covering at the same location by a continuous row of machine stitches.

7. The method as defined in claim 6 in which a trim strip is secured at the same location by a continuous row of machine stitches.

8. The method of manufacturing fabric lamp shades having lowermost and uppermost rings held in spaced axial relation comprising applying an enclosing covering to each of said uppermost and lowermost rings, and securing a fabric covering layer to each of said enclosing coverings axially outwardly beyond its ring by a continuous row of machine stitches and under tension between said rows of stitches.

9. The method of manufacturing fabric lamp shades having lowermost and uppermost rings held in spaced axial relation, comprising applying an enclosing covering to each of said uppermost and lowermost rings, securing a fabric covering layer to each of said enclosing coverings axially outwardly of its ring by a continuous row of machine stitches and under tension between said rows of stitches, and securing in spaced relation to the first covering layer another covering layer to the same enclosing coverings at the same locations by continuous rows of machine stitches and under tension between said rows of stitches.

10. The method as defined in claim 9 in which a trim strip is secured at the same location of said coverings by a continuous row of machine stitches.
